UNITED STATES PATENT OFFICE.

ERNEST M. HUNTER, OF RICHMOND, VIRGINIA, ASSIGNOR TO THE CARDWELL MACHINE CO., OF RICHMOND, VIRGINIA, A CORPORATION OF VIRGINIA.

APPARATUS FOR FILLING AND HEADING HOGSHEADS OF TOBACCO.

1,097,924.

Specification of Letters Patent.

Patented May 26, 1914.

Application filed May 7, 1913. Serial No. 766,166.

To all whom it may concern:

Be it known that I, ERNEST M. HUNTER, a citizen of the United States, residing at Richmond, in the county of Henrico and 5 State of Virginia, have invented certain new and useful Improvements in Apparatus for Filling and Heading Hogsheads of Tobacco; and I do hereby declare the following to be a full, clear, and exact description 10 of the same, reference being had to the accompanying drawings, forming part of this specification, and to the figures and letters of reference marked thereon.

This invention relates to apparatus designed for facilitating the filling of hogsheads with tobacco or similar elastic material, and more especially to the means for holding the heads during the time the workmen are engaged in "lining the hogshead 20 out" or permanently securing the head in place.

In the accompanying drawings, Figure 1 is an elevation, more or less diagrammatic in character, of a hydraulic press in which 25 there is embodied the present invention. Fig. 2 is a detail of one of the supports and bearings for the head holder or auxiliary plunger.

Like letters of reference in the two figures indicate the same parts.

The press illustrated is in its general characteristics similar to presses now in common use, and embodies a press frame formed by top and bottom timbers A and 35 A' connected by tension rods B, usually four in number, and arranged in the form of a rectangle. Extending below the bottom timbers A' is a hydraulic press cylinder C within which works a piston c carrying at 40 its upper end a movable platen D. The platen D is adapted to drop down to a point in proximity to the level of the floor whereby it will not obstruct the movements of a truck E which is adapted to be rolled over the 45 same and to carry a hogshead F into position to be lifted by the upward movement of the platen. Above and in line with the platen D is a plunger preferably formed by a flat head G supported from the top timbers A by vertically arranged posts or compression members H of sufficient strength to 50 withstand the compressive force exerted by the platen in compressing the tobacco in the hogshead.

55 A sufficient space is left below the plun-

ger head G and the top of the hogshead when the latter is in its lowered position for the insertion of a removable curb indicated in the drawings by the dotted lines I. In operation the hogshead and curb are both 60 filled with tobacco and when elevated by the platen D the tobacco is forced through the bottom of the curb down into the hogshead.

In accordance with present practice the 65 tobacco is pressed for a considerable distance down into the hogshead, say approximately one-third of the way, the hogshead is lowered, removed from the press and the head inserted, but it frequently happens 70 that before the heading operation is completed the tobacco heaves or swells and repressing is necessary before the hogshead can be closed. To overcome this difficulty I now propose to head the hogshead while in the 75 press and in order to avoid the necessity of elevating the hogshead, after the removal of the curb, to a point where the head and the tobacco confined thereby will be within the upper end of the hogshead, I provide a supplemental or auxiliary plunger which is 80 adapted to be swung into position below the main plunger G leaving a sufficient space below the auxiliary plunger for the permanent head K of the hogshead. The auxiliary 85 plunger which is interposed between the head K and the plunger G is preferably of skeleton form having top and bottom heads L connected by intermediate posts L', the bottom head L being preferably 90 considerably smaller than the permanent head K of the hogshead, whereby a space will be left all around the same for the manipulation of the tools in effecting the permanent attachment of the head K to the side wall of 95 the hogshead.

The auxiliary skeleton-like plunger L, L', is supported on swinging arms M carried by split bearings m surrounding one of the vertical tension rods B and the bearings m 100 are limited in their downward movement by adjustable split collars N secured to the rod B by means of clamping screws or otherwise, whereby the supplemental plunger is free to be swung to the position shown in full 105 lines in Fig. 1 over the hogshead, or to one side of the press as shown by the dotted lines in said figure, so as to be entirely out of the way and permit of the operation of the press in the ordinary manner. By 110

mounting the supplemental plunger on supports which are free to move upwardly, strain on the supporting members when the heading operation is proceeding is substantially eliminated and at the same time the supplemental plunger will be held at the proper level to swing in close under the plunger G so as to substantially fill the space between said plunger G and the top of the 10 hogshead when the latter is in lowered position.

With this appliance it is a comparatively simple operation to first press the tobacco down into the hogshead, then lower the hogshead, remove the curb and swing the supplemental or auxiliary plunger into position, having first, if so desired, placed the permanent head K of the hogshead on the latter. A very slight upward movement of the 20 hogshead is then all that is necessary to bring the permanent head down to its final seat and while so held the operation of fastening the same permanently in place is performed in the usual manner.

Having thus described my invention what I claim and desire to secure by Letters Patent of the United States is,—

1. The combination with a vertically arranged tobacco press embodying an upwardly movable platen adapted to form the pressing support for a hogshead or other receptacle, a main plunger supported in opposition to said platen, and a laterally movable auxiliary plunger of less diameter than the permanent head of the hogshead adapted to be interposed between the platen and main plunger for retaining the permanent head of the hogshead while being secured in place.

2. The combination with a tobacco press embodying a vertically movable platen adapted to form a hogshead support and a fixed plunger mounted in opposition to

said platen for forcing the tobacco down into the hogshead, and a laterally swinging auxiliary plunger movable into and out of alignment with the platen and plunger and in a plane in proximity to the plunger whereby the hogshead may be lowered to a point below the plane of movement of the auxiliary plunger and the latter swung into position for retaining the permanent head of the hogshead while being secured in place.

3. The combination with a vertically arranged tobacco press embodying an upwardly movable platen adapted to form the pressing support for a hogshead, a fixed plunger mounted in opposition to said platen, vertically arranged tension rods interposed between the platen and plunger carrying members, of an auxiliary plunger pivotally supported on one of said tension rods to swing laterally into and out of alignment between the platen and plunger, and means whereby said auxiliary plunger will be supported against downward movement but is free to move upwardly into contact with the fixed plunger.

4. The combination with a tobacco press embodying top and bottom timbers, tension rods connecting said timbers, a vertically movable platen supported by the bottom timbers, a downwardly projecting plunger supported by the top timbers in opposition to the platen, of an auxiliary plunger, swinging arms on which said auxiliary plunger is mounted having bearings surrounding one of said tension rods, and adjustable collars mounted on said rods and forming the supports for the swinging arms of the auxiliary plunger.
